DETACHABLE CONNECTING MEANS

Alex F. Hillstrom and Victor Petterson, Chicago,
Ill., assignors to Henry B. Floyd, Chicago, Ill.

Application June 25, 1927. Serial No. 201,314

7 Claims. (Cl. 5—294)

This invention relates to detachable connections and more particularly to bed post attaching means, although it may be employed with equal advantage for other purposes.

5 It contemplates more especially the provision of means for enabling the ready association and disassociation of complementary members to effect a rigid detachable joinder therebetween.

Numerous devices have heretofore been proposed for effecting the ready association and disassociation of complementary units, but these have not proved entirely satisfactory in that they are expensive, and not entirely effective in assembling complementary members with facility; 15 therefore much inconvenience and labor is entailed in the use thereof.

Further, it is exceedingly desirable to provide means for effecting a joinder of complementary members in reversible positions so as to enable 20 the disposition thereof in variable relation with facility.

One object of the present invention is the provision of novel means for effecting the rigid association or disassociation of complementary elements.

Another object is the provision of slidable cooperating means to effect the ready association and disassociation of members.

A further object is to provide simple and inexpensive means for enabling the detachable connection of members disposed in rigid relation to each other.

A still further object is to provide means capable of variable co-operation to enable reversible connection therebetween.

Still a further object is to provide means to effect a rigid joinder between complementary members of a bed to enable convenient assembly thereof.

40 Other objects and advantages will appear from the following description of an illustrated embodiment of the present invention.

In the drawing:

Figure 1 is a sectional view in elevation of a 45 device embodying features of the present invention;

Figure 2 is a view in elevation disclosing complementary members of a bed assembled in a reversed position;

Figure 3 is a plan view in section taken substantially along the line III—III of Figure 1;

Figure 4 is a side view in elevation of the device disclosed in Figure 1;

55 Figure 5 is a view in elevation of one of the

engaging means employed in association with a member; and

Figure 6 is a view in elevation of means capable of co-action with the means disclosed in Figure 5 to effect a rigid joinder between complementary 60 members.

The structure selected for illustration is shown in association with complementary members constituting component parts of a bed frame; however, it may be employed with equal advantage 65 for effecting a rigid joinder between other members.

The complementary members comprise, in this instance, a bed post 10 consisting of the usual metallic tube preferably though not essentially 70 of rectangular configuration. To enable a rigid joinder of the bed post 10 with parallel disposed bars 11 disposed between the end faces of the bed to constitute the spring support, a plate 12 is riveted or otherwise fixed to the bed posts 75 10 by virtue of its angularly related shank 13 which has an arcuate depression 14 co-actable with the exterior of a round post as distinguished from the flat surface with which it is shown to contact. A member 15 is disposed 80 within the post 10 to receive fasteners such as the rivets 16 therethrough, thereby permanently affixing the plate 12 to the post 10.

It is to be noted that the member 15 has an 85 arcuate surface 17 constituting a segment of a circle so that it can be reversed to contact with a circular surface of a round post. This arrangement enables the attachment of the plate 12 to either a flat or arcuate surface which are interchangeably used in the manufacture of beds. 90

As shown, the member 12 projects from the face of the bed post 10 and terminates in an arcuate edge 18 which is shaped to define a hook 19 in communication with a vertically disposed slot 15 95 communicating with an edge thereof. Obviously in the slot 20 may be provided in the plate 12 in any suitable position it preferably extending in a vertical direction to receive a member complementary thereto to effect a rigid joinder between the angle bars 11 arranged to maintain a bed 100 spring thereon.

To enable the ready association and disassociation of the bars 11 with respect to the bed post 10, means capable of cooperation with the slot 20 are affixed thereto. The cooperating means consist in this instance of an elliptical plate 22 having one edge 23 thereof substantially straight to coact with a correspondingly shaped edge of the slot 20. The other edge 24 thereof tapers toward 105 a midpoint 25 which is removed sufficiently from 110

the edge 23 to permit the disposition of the plate 22 within the slot 20. It is to be noted that the tapering edges 24 facilitate the reception of the plate 22 within the slot 20 in either direction, the portion 25 contacting with the edge of the slot 20 in operative position to insure a rigid connection therebetween without permissive lateral movement.

Accidental removal of the plate 22 from the slot 20 is prevented by associating a plurality of discs 26, in this instance three, with the plate 22 in any appropriate manner so that portions thereof will project beyond the edges of the plate 22 to insure the guided disposition thereof within the slot in only a vertical direction, the projecting peripheral edges 27 of the discs 26 being spaced from the face of the bars 11 by the plate 22 to form a guideway therebetween to receive the slotted plate 12.

The discs 26 consist in this instance of a plurality of circular plates having reduced shanks 28 which project through suitable apertures in the plate 17 and bars 11 so that the extremities thereof may be flattened as at 29 to maintain the discs 26 and plate 22 fixed to the bars 11. The circular discs 26 are preferably disposed in alternate relation so that the portions thereof projecting over the plate 22 define a guide on both the edges 23 and 24, the latter edge being provided with a circular disc 26 at the point 25 defined by the angularly related portions thereof. The other discs 26 overlap the edge 23 near the extremities of the plate 22 to slidably guide the complemental members 10 and 11 to a position effecting a rigid joinder therebetween. It is to be noted that the plate 22 having the discs 26 fixed thereto to define projecting flanges 27 can be introduced within the slot 20 from either end thereof, thereby enabling the bars 11 which preferably are of angular cross-section to be reversed. This arrangement is very advantageous in bed constructions, not only because it affords the disposition of bed springs 30 thereon at various altitudes, but also effects the confinement thereof within predetermined limits defined by the vertical flange 31 of the angle bar 11. (Fig. 1.)

It will be apparent that novel means have been provided to enable the ready association and disassociation of complemental members so that they may be assembled with ease and without entailing much labor and expense.

Various changes may be made in the embodiment of the invention herein specifically described

55

without departing from or sacrificing any advantages thereof as defined in the appended claims.

We claim:

1. Complemental members, one having a slot therein, the other member having a plate affixed thereto for introduction into said slot, said plate being shaped to enable the reception thereof into said first member in reversed positions, and discs alternately spaced on said plate to extend over the edges thereof to define a guideway for said slotted member.

2. Complemental members, one comprising a slotted plate, the second comprising a plate shaped to substantially correspond with the slot in said first member, and a plurality of discs affixed to said second plate in projecting relation for coaction with said slotted plate to define a guideway therefor.

3. Complemental members, each of said members having plates affixed thereto, there being a slot in one of said plates to slidably receive the other of said plates, and means upon said latter plate for preventing lateral displacement of said plate from said slot, said means including a plurality of discs projecting beyond the edges of said plate for coaction with said slotted plate.

4. Complemental members comprising plates, one of said plates having a slot to slidably receive the other of said plates, and a plurality of alternately arranged lugs having portions thereof of projecting beyond the edge of said other plate to define a guideway for said slotted plate.

5. Complemental members having cooperating means to establish a detachable connection therebetween, said cooperating means comprising a plate having a slot therein, another plate shaped to correspond with said slot, and a plurality of discs on said latter plate arranged so that portions of said discs extend beyond the edges of said plate to define a guide for said first mentioned plate.

6. Complemental members comprising plates, one of said plates having a slot to slidably receive the other of said plates, and a plurality of alternately arranged members having portions thereof projecting beyond the edge of said other plate to define a guideway for said slotted plate.

7. The complemental members described in claim 6, and in which the plate insertable into the slot in the other member is reversibly dis-posable in said slot.
